UNITED STATES PATENT OFFICE.

HUGO TUECKMANTEL, OF NEWARK, NEW JERSEY, ASSIGNOR TO T & L CO., INC., OF NEWARK, NEW JERSEY, A CORPORATION OF NEW JERSEY.

BAG-FRAME LOCK.

Application filed February 28, 1924. Serial No. 695,654.

To all whom it may concern:

Be it known that I, HUGO TUECKMANTEL, a citizen of the United States, residing at Newark, in the county of Essex and State of New Jersey, have invented new and useful Improvements in Bag-Frame Locks, of which the following is a specification.

This invention relates to improvements in key actuated locks in which a bolt element is moved relative to its keeper by suitable manipulation of a key, types of which are commonly and widely known, that selected for illustration being a conventional bag frame lock.

One of the objects of the invention is to provide a fixed longitudinal member within the body of the lock, through which the bit and stem of the key passes, guiding the key its entire length, preventing it from becoming misplaced or entangled and also from being turned prematurely.

Another purpose is to produce a key guide that tends to prevent the use of an improper key and by the use of which the usual fixed guide pin or post may be dispensed with and the consequent drilling of the key stem.

A further aim is in the provision of a key guiding device which operates to strengthen and re-enforce the lock casing, particularly the extending portion thereof which is frequently subject to blows and collisions with other objects.

With these and other analogous aims and objects in view, the invention consists in the novel construction and arrangement of parts hereinafter described and shown in the annexed drawing, forming a material part of this disclosure, and in which:—

Figure 1 is a perspective view of a lock 40 as assembled on the frame of a bag.

Figure 2 is a sectional view in perspective, showing the interior of the lock and drawn to an enlarged scale.

Figure 3 is a transverse sectional view 45 taken on line 3—3 of Figure 2.

Figure 4 is a partial end elevational and central vertical sectional view of the same.

Figure 5 is a view similar to Figure 2, but 50 showing a modification in which the key guide post is omitted.

Referring more in detail to the drawing, the numeral 10 designates in general the main portion of the lock casing, the same having outstanding end flanges 11 on one

side to provide means for securing the lock 55 rigidly on the part to which it is applied.

In the upper portion of the front wall of the casing are openings 12 adapted to receive keepers (not shown) the same being engageable by bolts 13 operable within the 60 casing.

On the top wall of the casing is fixed the flanges of a hollow upstanding guide bracket 14, open at both ends, the inner of which registers with an opening of corresponding dimensions in the top wall of the casing.

Movable in this opening and extending normally past the bracket 14, to which it is neatly fitted, is a hollow bolt release slide 70 15, its outer end wall containing a key entrance opening 16.

The lower end of this slide is fixed in the raised member 17 of a plate 18 rigidly fixed on a corresponding plate 19 and having between them an intermediate plate 20 containing a key hole 21, the lowermost plate 19 having a central lowered portion 22.

Fixed in this element 22 is a post 23 extending upward in register with the key holes 21 and 16 and adapted to enter the opening 24 in the shank or stem of the key 25, the same having a ward or bit 26 containing a recess permitting it to pass the plate 20 when the key is turned, said plate preventing the use of a spurious key in an obvious manner.

The bolts 13 are carried by the plates 18, 19 and 20 which are rigidly engaged together to operate as an entity and are held 90 in a normally raised position, together with the slide 15, by springs 27 and are guided by pins, not shown, operating in the openings 28.

From the foregoing it will be seen that 95 a key with a relatively long stem or shank is used, the entering end of which must be accurately guided, and more particularly if no post is used, as illustrated in Figure 5.

In order to provide an efficient guide for the keys of such locks and which will permit the omission of the post, and consequent drilling of the key stem, a guide tube 30 having lateral flanges 31 to suit the ward of the key, the stem 25 of which fits the tube, is 105 inserted between the upper wall of the side 15 and a plate 29 fixed at the lower end of the slide.

This guide tube 30 is held in position by flanged partitions 32 and 33 fixed transversely in the slide and which positively directs the passage of an entered key from the escutcheon 16 to the key hole 21 rendering it impossible to enter the key at an angle, to allow it to become entangled and which permits dispensing with the post.

Furthermore the construction very materially re-enforces the extending portion of the lock, subject to accidental injury as it is, besides providing means for entering a key in a convenient and proper manner.

It will be understood that the application of a key guide tube is by no means limited to bag frame locks but is equally applicable to a wide range of lock types in which a key is used having a ward or bit extending from its cylindrical shank or stem.

While certain preferred embodiments of this device have been shown and described, it will be understood that changes in the form, arrangements, proportions, sizes and details thereof may be made without departing from the scope of the invention as defined in the appended claims.

Having thus described my invention, what I claim as new and desire to secure by Letters Patent, is:—

30 1. A key operated bag lock comprising a casing, a slide movable transversely therein, a bolt movable in said casing, a key for actuating said bolt, and an unbroken key guide fixed in said slide extending longitudinally from the key entrance opening to the plane of application of the key to said bolt.

35 2. A key operated bag lock comprising a casing having a central raised slide movable therein, a bolt movable in said casing, a key for actuating said bolt, an integral key

guide tube fixed in said slide extending longitudinally from the key entrance opening to the plane of application of the key to said bolt, and lateral flanges on said tube adapted to engage the bit of said key therebetween. 45

3. A key operated lock comprising in combination with a casing, a bolt movable in said casing, and a key for actuating said bolt, of an open sided key guide tube fixed in said casing extending longitudinally from the key entrance opening to the plane of application of the key to said bolt, lateral flanges on the inner end of said tube adapted to engage the bit of said key therebetween, 50 and supports for said guide tube anchored in said casing to act as a re-enforcement therefor. 55

4. A key operated lock comprising in combination with a casing, and a key, of a raised transverse slide movable in said casing, a guide tube for said key, said tube being open at one side and extending uninterruptedly throughout the slide from the entrance opening of said key to its point of application, and transverse elements in said slide rigidly supporting said tube. 60

5. A lock comprising a casing, a bracket extending thereabove, two or more plates united to form a bar movable in said casing in the plane of said bracket, a covered slide having a key entrance fixed to said bar, a tubular key guide of unbroken length fixed in said slide below the entrance to extend the full length thereof, and means carried by said bar to prevent a spurious key from turning therein. 70 75

This specification signed and witnessed this 25th day of February, 1924.

HUGO TUECKMANTEL.
